UNITED STATES PATENT OFFICE

162,719

EMBOSSED PLASTIC SHEET OR SIMILAR ARTICLE

William M. Feder, New York, N. Y.

Application July 12, 1950, Serial No. 11,086

Term of patent 7 years

(Cl. D87—3)

To all whom it may concern:

Be it known that I, William M. Feder, a citizen of the United States, residing at New York city, in the county of New York and State of New York, have invented a new, original, and ornamental Design for an Embossed Plastic Sheet or Similar Article, of which the following is a specification, reference being had to the accompanying drawing, forming part thereof.

In the drawing

The single figure of the drawing is a top plan view of an embossed plastic sheet or similar article, showing my new design.

I claim:

The ornamental design for an embossed plastic sheet or similar article, as shown.

WILLIAM M. FEDER.
